UNITED STATES PATENT OFFICE.

ELMER A. KLAPP, OF NEW YORK, N. Y.

DESIGN FOR A BADGE OR SIMILAR ARTICLE OF MANUFACTURE.

53,452.

Specification for Design.

Patented June 17, 1919.

Application filed March 4, 1918. Serial No. 220,403. Term of patent 3½ years.

To all whom it may concern:

Be it known that I, ELMER A. KLAPP, a citizen of the United States, residing at New York, in the county of New York and State of New York, have invented a new, original, and ornamental Design for a Badge or Similar Article of Manufacture, of which the following is a specification, reference being had to the accompanying drawings, forming part thereof.

The figure is a view showing a badge or similar article of manufacture embodying my design.

I claim:

The ornamental design for a badge or similar article of manufacture.

ELMER A. KLAPP.

Witnesses:

R. C. COLMAN,
L. GORDON.
